UNITED STATES PATENT OFFICE.

THOMAS K. VERLIN, OF NASHVILLE, TENNESSEE.

LATH OR PLASTER BASE.

Application filed January 28, 1924, Serial No. 689,090. Renewed February 8, 1926.

This invention relates to improvements in lath or sheathing constructions adapted to support plaster or other cementitious material.

5 The primary object of this invention is the provision of a relatively simple and inexpensive type of lath construction which is very durable, and which may be so used in building constructions as to directly support 10 the plastering coat thereon without the necessity of providing the conventional mortar coatings.

A further object of this invention is the provision of a lath or sheathing construction 15 which may be used for economically constructing walls and ceilings, as the same is of such nature as to effectively receive a plastering coat directly thereon, without the necessity of providing the conventional scratching or browning coats, and in this respect not only being economical, from a 20 material saving standpoint, but doing away with the necessity of operations now necessary and used with ordinary lathing.

25 The metal lathing now in use for supporting mortar and plaster walls is subject to oxidation incident to intimate contact of the wet cementitious mass directly thereon, and this type of lathing is subject to extreme 30 expansions and contraction incident to temperature variations. As a result it is necessary to place heavy coatings of mortar on metal lathing prior to the placing of the finishing coat or plastering. There is also in use a type of lathing formed of paper material which is of itself not sufficient to support walls of any considerable weight, incident to the fact that absorption of moisture by the paper lathing will permit the 35 same to buckle and incident to weight of the cementitious material the paper lathing is very often ruptured. With the improved lathing a rigid lath base is provided which has secured thereover an absorbent or fibrous 40 body somewhat yieldable and to which plaster readily adheres, so that the plaster is not directly subject to the rapid expansions or contractions incident to temperature 45 variations which might affect a rigid base.

50 Other objects and advantages of this invention will be apparent during the course of the following detailed description.

In the accompanying drawing, forming a part of this specification, and wherein similar reference characters designate corresponding parts throughout the several views,

Figure 1 is a fragmentary front elevation of studding of a wall construction, showing the application of the details of the improved lathing thereon.

Fig. 2 is a cross sectional view taken through the lathing substantially on the line 2—2 of Figure 1.

Fig. 3 is a fragmentary front elevation showing the application of plaster to the improved lathing, and

Fig. 4 is a cross sectional view taken through the improved lathing construction showing the manner in which a plaster coating may be keyed thereto.

In the drawing, wherein for the purpose of illustration is shown only the preferred embodiment of this invention the letter A may generally designate the lathing, which consists of a supporting sheet B of rigid material; and a less rigid and somewhat yieldable and absorbent sheet of plaster supporting material C fixedly secured over the entire area of the backing material B.

The base B of the lathing or sheathing A is preferably of sheet metal, rigid throughout. The material C is preferably some absorbent, yieldable, or fibrous material such as cardboard, felt, asbestos, gravel surfaced paper or the like. The sheets B and C are of the same dimensions, a convenient size of lathing or sheathing being four feet by two feet. The facing surfaces of the sheets B and C are placed in abutment through the length and width of the sheets, and they are fixedly secured together in any approved manner, although preferably by punching apertures through the sheets B and C from the rear side of the supporting sheet B, thus providing tubular projections 15 which extend into the material of the sheet C in a crimped relation therein, fixedly holding the sheets B and C in a stable and a non-detachable relation. Thus openings 16 are formed through the lathing A. The punching of these openings into the absorbent or flexible sheet C will provide annular projections 18 about the openings 16, on the plaster receiving face of the sheet C. This provides a roughened surface for the plaster receiving face of the sheet C, and more readily enables the plaster or other cementitious material to adhere thereto.

In lieu of sheet metal for the rigid back sheet B, boards may be used, although the most economical and the most efficient combination for average use will be that of pro-

viding a thin sheet metal supporting back B with a cardboard plaster receiving sheet C affixed thereto in the manner above described.

5 The sheets of lathing or sheathing A are, of course, attached by suitable nails or securing elements 20 to the studding E to provide a wall, and after the sheathing or lathing has been so applied it is merely necessary

10 to place the plastering or other cementitious coat on the exposed surface of the sheathing. The plaster will, incident to the troweling operation, find its way into the openings 16, and small projections may form rearwardly

15 of the sheet B about the openings, to effectively key the plaster coat to the lathing or sheathing, as can readily be understood.

It will, of course, be apparent that the sheet B furnishes the necessary rigidity and 20 supporting medium for the plastering of the wall, and the plaster or cementitious material is separated from the metal sheet B by means of the absorbent, yieldable, and fibrous material C which furnishes the necessary condensing and suction medium for 25 the plaster coating.

With the above described improved type of lathing it is not necessary to provide the fiber mixed mortar coatings, and a relatively 30 light weight wall may be provided in a minimum time and with less expense than is now customary. The plaster coating will adhere to the sheathing and cannot be jarred loose therefrom incident to ordinary vibrations, 35 because of the fact that there is a buffering surface provided in the yieldable sheet C. The improved type of lathing is especially useful under extreme conditions of usage, and will readily absorb moisture, withstand vibration, frost, expand and contract incident to 40 temperature variation, and will stand extraordinary surface abuses.

It is, of course, realized that numerous ways may be used for keying or securing the 45 plaster coating in adhering relation to the lathing, and it has even been contemplated to provide projections of a stub nature for securing the sheets B and C together and the plaster thereto.

50 Various changes in the shape, size, and arrangement of parts may be made to the form of invention herein shown and described, without departing from the spirit of this invention or the scope of the claims.

55 I claim:

1. As an article of manufacture a lath comprising a sheet metal supporting back, and a yieldable absorbent plaster receiving sheet, said sheet metal being punched at intervals 60 to provide spaced plaster receiving openings extending through said lath and annular

flanges about the openings of the sheet metal and plaster receiving sheet, the flanges of the sheet metal extending into the openings of the plaster receiving sheet to hold the sheets 65 together and the flanges of the plaster receiving sheet adapted to be embedded in plaster placed thereon and retain the plaster in place.

2. As an article of manufacture a sheath- 70 ing construction comprising a polygonal sheet of metal, and a similarly formed sheet of plaster receiving material, said metal and plaster receiving material being placed in abutting relation and the sheathing stamped 75 at spaced points from the exposed side of the metal to provide openings and fastener members disposed circumferentially about the openings of the metal and moved into the openings of the plaster receiving material 80 into crimping relation with the plaster receiving material to retain the sheets together.

3. A lath construction comprising a sheet metal supporting member and a plaster receiving sheet placed in face to face engagement with said supporting member, the sheet metal supporting member being punched through from its exposed face to provide openings in the lath and also provide tongues embedded in the plaster receiving sheet to secure the plaster receiving sheet to the supporting member, the plaster receiving sheet between the openings being free from the supporting member. 85 90

4. As an article of manufacture, lathing 95 comprising flat sheets in face to face engagement, one being a sheet of metal and the other a sheet of absorbent material, the lathing being punched from the exposed face of the sheet of metal in a multiplicity of places 100 to provide openings in closely arranged staggered relation and tongues extending from the sheet of metal into the sheet of absorbent material and constituting the sole means for anchoring the absorbent material to the sheet 105 of metal.

5. As an article of manufacture lathing comprising a flat rigid supporting sheet of metal, a flat sheet of absorbent material in abutting conforming relation at one side of 110 said flat sheet of metal, said sheets having a plurality of closely spaced openings punched therethrough from the sheet of metal into the sheet of absorbent material to provide crimping flanges which connect the sheets together and provide a roughened face at the absorbent material side of the attached sheets, and a plaster sheet of cementitious material secured in said openings and by said crimping flanges at the roughened absorbent material side of the sheets. 115

THOMAS K. VERLIN.
